UNITED STATES PATENT OFFICE.

ROBERT JULIUS MAREBURGER, OF DALLAS, TEXAS.

TIE-BAR.

SPECIFICATION forming part of Letters Patent No. 780,433, dated January 17, 1905.

Application filed July 1, 1904. Serial No. 214,977.

To all whom it may concern:

Be it known that I, ROBERT JULIUS MAREBURGER, a citizen of the United States, residing at Dallas, in the county of Dallas and State of Texas, have invented new and useful Improvements in Tie-Bars, of which the following is a specification.

My invention relates to new and useful improvements in tie-bars for railways; and its object is to provide a simple and inexpensive device of this character which can be readily attached to rails and which will effectually prevent spreading thereof.

A further object is to provide a device of this character adapted to be used in connection with but removed from the ordinary railway-ties.

With the above and other objects in view the invention consists of a bar having hooked ends adapted to engage the outer flanges of the rails of a track, and secured to these bars are locking-plates for engaging the inner flanges of the rails, and thereby rigidly fastening the rails together and preventing spreading thereof.

The invention also consists in the further novel construction and combination of parts, hereinafter more fully described and claimed, and illustrated in the accompanying drawings, in which—

Figure 1 is a perspective view of my improved bar in position upon rails. Fig. 2 is a longitudinal section therethrough. Fig. 3 is an enlarged section on line 3 3, Fig. 2; and Fig. 4 is a perspective view of one of the locking-plates detached.

Referring to the figures by numerals of reference, 1 is a metal bar of any desired proportions and having hooks 2 at its outer ends adapted to extend over the outer base flanges 3 of rails 4. Secured to these bars are locking-plates 5, having side flanges 6, adapted to overlap the edges of the bar 1, and a tongue 7 is formed at one end of the plate and serves to overlap the inner flange 8 of one of the rails 4, thereby holding said rail securely in position upon the tie-bar. The locking-plates

5 are adapted to be secured to the tie-bar by means of bolts 9 or other suitable fastening devices arranged within apertures 10, formed 50 in the tie-bar and the locking-plates.

It will be seen that this invention is very simple and inexpensive in construction and can be readily secured to the rails and after once placed in position thereon will effectually prevent them from spreading. The tie-bars are used in connection with but removed from the ordinary railway-ties 10^a. As is well known, the insertion of spikes into a wooden railway-tie often results in the splitting of the 60 same, and as a result thereof spreading of the rails often occurs. The use of the tie-bar herein described, however, prevents this displacement of the rails, and therefore the danger of accidents from this cause is minimized. 65

In the foregoing description I have shown the preferred form of my invention; but I do not desire to limit myself thereto, as I am aware that modifications may be made therein without departing from the spirit or sacrificing any of the advantages thereof, and I therefore reserve the right to make such changes and alterations as fairly fall within the scope of my invention. 70

Having thus fully described the invention, 75 what I claim as new, and desire to secure by Letters Patent, is—

The combination with a tie-bar having integral hooks at the ends thereof for engaging the outer base-flanges of rails; of locking-plates upon the tie-bar, flange-engaging tongues integral therewith and inclined toward the hooked ends of the tie-bar, a flange integral with and extending from one end to the other of each side of each locking-plate, 80 said flanges being adapted to overlap the sides of the tie-bar, and means for securing the locking-plates upon the tie-bar. 85

In testimony whereof I affix my signature in presence of two witnesses.

ROBERT JULIUS MAREBURGER.
